NEW YORK, ASSIGNEES TO WESTERN ELECTRIC COMPANY, INCORPORATED, OF NEW
YORK, N. Y., A CORPORATION OF NEW YORK.

TELEPHONE-EXCHANGE SYSTEM.

1,263,376.

Specification of Letters Patent. Patented Apr. 23, 1918.

Application filed November 9, 1916. Serial No. 130,372.

To all whom it may concern:

Be it known that we, HENRY P. CLAUSEN and CHARLES L. GOODRUM, citizens of the United States, residing at Mount Vernon, in the county of Westchester and State of New York, and at Brooklyn, in the county of Kings and State of New York, respectively, have invented certain new and useful Improvements in Telephone-Exchange Systems, of which the following is a full, clear, concise, and exact description.

This invention relates to telephone exchange systems and more particularly to such systems in which trunk circuits are employed for interconnecting subscribers' lines terminating in different central offices.

The object of this invention is the provision of improved signaling means for such systems whereby the time required for establishing connections between subscribers may be reduced.

In accordance with this invention, there is provided at each end of a trunk circuit apparatus which coöperates upon the connection of a link circuit with one end thereof to select the character of ringing current to a called line, thereby determining which of a plurality of stations on a telephone line connected with the other end of the trunk circuit is to be signaled.

This invention, in one of its embodiments, is illustrated in the accompanying drawing, showing a trunk circuit C extending between two central offices, the apparatus to the left of the vertical dotted line being located at the first or originating central office and that to the right thereof being located at the second or terminating central office. A cord circuit A (a portion only of which is shown), located at the first central office, may be employed in connecting a calling telephone line (not shown) with the outgoing end of the trunk circuit C. The incoming end of the trunk circuit C, terminating at the second central office, may be connected with the jack of a telephone line B, to which are connected four stations, D, E, F and G, the apparatus of which is of the usual construction, the call bells of the different stations being tuned to respond to alternating currents of different frequencies.

Before proceeding with the operation of the system shown in the drawing, a word

of explanation regarding some of the apparatus employed may be in order.

Located at the first central office, and associated with the trunk circuit, are four jacks 5, 6, 7 and 8, the contacts of which are connected with fixed terminals of an automatic switch 9. Associated with the four jacks are four relays 15, 16, 17 and 18, there being one individual to each jack, and a relay 14 common to all four jacks. A motor magnet 10, when actuated, serves to rotate the brushes 11, 12 and 13 of the automatic switch 9 over the fixed terminals thereof. The automatic switch 9 is of the step-by-step type, the stepping pawl of which is controlled by the motor magnet 10, and the holding pawl by release magnet 32.

The holding pawl is normally in engagement with the ratchet wheel of the automatic switch 9 and is withdrawn therefrom when the release magnet 32 is actuated to permit the switch to return to its normal position.

Located at the other end of the trunk circuit, there is an automatic switch 29 having four fixed terminals, to which are connected four generators 25, 26, 27 and 28 for generating alternating currents of different frequencies. A movable contact 21 of the automatic switch 29 is controlled by a motor magnet 20, adapted to be actuated in synchronism with the motor magnet 10. The automatic switch 29 is also of the step-by-step type, the stepping pawl of which is controlled by motor magnet 20 and the holding pawl by a release magnet 42. The holding pawl is normally out of engagement with the ratchet wheel of the switch 29 and is brought into engagement therewith upon the actuation of release magnet 42.

The operation of the system shown in the drawing will now be described. The operator at the first central office, having been advised that connection is desired with a subscriber whose line terminates at the second central office, communicates the number of the wanted line to the operator at the second central office over a call wire circuit (not shown) and receives a trunk assignment. Assuming that trunk circuit C has been assigned, and that subscriber G on line B, whose call bell is tuned to respond to current from generator 28, is the subscriber

With whom connection is desired, the operator at the first central office inserts the plug of cord circuit A into jack 8, whereupon relays 14 and 18 operate, the operation of the former energizing slow release relay 30, and the latter connecting ground to the test terminal of the automatic switch 9, associated with jack 8. The actuation of slow release relay 30 completes an operating circuit for motor magnet 10, but before the motor magnet operates, relay 40 operates, due to an impulse of current from battery, through winding of release magnet 32 (which is marginal and does not operate when in circuit with relay 40), left-hand contact of relay 30, middle normal contact of motor magnet 10, left-hand winding of relay 40, right-hand normal contact of motor magnet 10, and right-hand contact of relay 30 to ground. Relay 40 operates, lighting lamp 41 and causing the operation of release magnet 42, which is slow in releasing. The actuation of release magnet 42 throws the holding pawl into engagement with the ratchet wheel of switch 29. The energization and operation of motor magnet 10 moves the brushes 11, 12 and 13 into contact with first or left-hand set of contacts, and closes an off-normal contact 31. Since the test terminal of the first set is not grounded, no circuit is completed for relay 33. The motor magnet 10, in operating, interrupts its own circuit at its left-hand contact. When the motor magnet 10 operated, its right-hand and middle normal contacts were opened, thereby releasing relay 40, whereupon motor magnet 20 and slow release relay 43 operate over a circuit from battery through the windings of motor magnet 20 and slow release relay 43 in parallel, contact 44 (which is closed when automatic switch 29 is in normal position), contact of release magnet 42 and normal contact of relay 40 to ground. Release magnet 42 being slow in releasing, holds its contact closed and the holding pawl in engagement with the ratchet wheel of switch 29 while the alternate contact of relay 40 is open during the stepping period.

50 The operation of motor magnet 20 advances movable contact or brush 21 of automatic switch 29 to the first contact to which generator 25 is connected, and opens contact 44 and closes contact 45 which is open when automatic switch 29 is in normal position. The operation of relay 43 opens its right-hand contact and closes its left-hand contact, which is now substituted for contact 44, opened by operation of motor magnet 20. Relay 43, being slow in releasing, its contacts remain closed while the normal contact of relay 40 is open during the stepping period. The closure of contact 45 does not permit relay 46 to operate, for the winding thereof is now short-circuited at its left-

hand normal contact and the contact of trip relay 47.

Since motor magnet 10, in operating, opens its operating circuit, it releases, whereupon relay 40 again operates. Motor magnet 20 thereupon releases. Motor magnet 10 when fully released again completes its operating circuit, whereupon it operates to advance brushes 11, 12 and 13 to the second position. Upon the operation of motor magnet 10, relay 40 releases to complete the operating circuit of motor magnet 20, which thereupon operates to advance brush 21 of switch 29 to the second terminal to which generator 26 is connected. Both motor magnets continue to operate the switches until the brushes of switch 9 advance to the fourth set of terminals, when relay 33 operates to lock up motor magnet 10, the circuit being from battery, winding of motor magnet 10 and relay 33, brush 13, test terminal of fourth set associated with jack 8, contact of relay 18 to ground. When motor magnet 10 is locked up, motor magnet 20, due to the release of relay 40, advances the brush 21 to the fourth terminal to which is connected generator 28. Upon the connection of the brushes of switch 9 with the fourth set of terminals corresponding to the jack 8 to which a cord circuit A is connected, relay 40 is operated from battery in the cord circuit A, and remains operated as long as the plug of the cord circuit is in the jack. Since relay 40 is now locked up, release magnet 42 is locked up, whereupon relay 43 releases, connecting alternating current from generator 28 to the ring contact of the plug of the trunk circuit by way of brush 21, winding of tripping relay 47, left-hand normal contact of relay 46, right-hand contact of relay 43. The operator at the second central office inserts the plug of the trunk circuit into jack of line B, operating sleeve relay 48 and connecting ringing current from generator 28 to line B to operate the call bell at station G. The operator at the terminating central office may of course connect the plug of the trunk circuit with the jack of line B as soon as a trunk assignment is made. The operation of relay 48 opens the circuit of lamp 41 and locks up release magnet 42 independent of the condition of the outgoing end of the trunk circuit. Upon the response of subscriber at station G, tripping relay 47 operates, removing the short circuit of relay 46, which now operates over a circuit from battery, through the winding of relay 46, resistance 49, and contact 45 to ground. Relay 46, in operating, opens its left-hand normal contact, thereby removing ringing current from the line. Supervisory relay 60 now operates over a circuit from battery through the winding of supervisory relay 60, left-hand alternate contact of relay 46, right-

hand contact of relay 43, ring contacts of the plug and jack out and back over line B, tip contacts of the jack and plug, and right-hand contact of relay 48 to ground. 5 Upon the actuation of supervisory relay 60, the right-hand winding of relay 40 is connected in parallel with the left-hand winding thereof to cause the operation of the supervisory relay in cord circuit A and extinguish the supervisory lamp (not shown). 10

Upon the conclusion of the conversation, subscriber G restores the receiver to the switchhook, releasing supervisory relay 60, whereupon the calling supervisory lamp in 15 cord circuit A lights to furnish a disconnect signal. The operator at the first central office thereupon withdraws the plug from jack 8. Relays 14 and 18 thereupon release, the release of the former causing the operation of release magnet 32 over a circuit from battery through the winding of release magnet 32, contact 31 and normal contact of relay 14 to ground. The operation of release magnet 32 withdraws the holding 20 pawl from the ratchet wheel of switch 9. The release of relay 18 permits the release of relay 33 and motor magnet 10, whereupon switch 9 returns to normal position opening contact 31, whereupon release magnet 32 releases. Upon the release of motor 25 magnet 10, relay 40 releases lighting the lamp 41 to furnish a disconnect signal to the operator at the second central office, who thereupon withdraws the plug from the jack releasing relay 48, thereby effacing 30 lamp 41 and releasing the release magnet 42, whereupon switch 29 is restored to normal position, opening contact 45 and closing contact 44.

10 What is claimed is:

1. A telephone exchange system comprising a trunk circuit extending from a first to a second central office, a plurality of sources of signaling current at the second central office, a plurality of terminals for the trunk circuit at the first central office corresponding to the sources of signaling current, a link circuit at the first central office, and an electro-magnetic switching device in the trunk circuit operating upon the connection of the link circuit with any one of the terminals to select the corresponding source of signaling current. 45

2. A telephone exchange system comprising a trunk circuit extending from a first to a second central office, a plurality of sources 50

of signaling current at the second central office, a plurality of terminals for the trunk circuit at the first central office corresponding to the sources of signaling current, a link 60 circuit at the first central office, and an automatic step-by-step switch in the trunk circuit operating upon the connection of the link circuit with one of the terminals to select the corresponding source of signaling 65 current.

3. A telephone exchange system comprising a trunk circuit extending from a first to a second central office, a plurality of sources of signaling current at the second central 70 office, a plurality of sets of terminals at the first central office corresponding to the sources of signaling current, a link circuit at the first central office, and an automatic step-by-step switch in each end of the trunk 75 circuit operating upon connection of the link circuit with one set of terminals to connect the trunk circuit therewith and to select the corresponding source of signaling current.

4. A telephone exchange system comprising a trunk circuit extending from a first to a second central office, a plurality of sources of signaling current at the second central office, a plurality of sets of terminals at the first central office corresponding to the 80 sources of signaling current, a link circuit at the first central office, an electromagnetic switching mechanism in each end of the trunk circuit operating upon connection of the link circuit with one set of terminals to 85 connect the trunk circuit therewith and to select the corresponding source of signaling current.

5. A telephone exchange system comprising a trunk circuit extending from a first to a second switchboard, a plurality of sources of signaling current at the second switchboard, a plurality of terminals for the trunk circuit at the first central office corresponding to the sources of signaling current, a link 95 circuit at the first central office, an electro-magnetic switching mechanism in the trunk circuit operating upon the connection of the link circuit with any one of the terminals to 100 connect the trunk circuit thereto and to 105 select the corresponding source of signaling current.

In witness whereof we hereunto subscribe our names this 8th day of November, A. D. 1916.

HENRY P. CLAUSEN.
CHARLES L. GOODRUM.
